UNITED STATES PATENT OFFICE.

ARTHUR W. SPRAGUE, OF LA GRANGE, ILLINOIS.

POST-ANCHOR.

1,167,852.

Specification of Letters Patent. Patented Jan. 11, 1916.

Application filed July 14, 1915. Serial No. 39,740.

To all whom it may concern:

Be it known that I, ARTHUR W. SPRAGUE, a citizen of the United States, residing at La Grange, in the county of Cook and State of Illinois, have invented certain new and useful Improvements in Post-Anchors, of which the following is a specification.

My invention relates to post anchors.

One of the objects of my invention is to 10 provide a post anchor which may be folded and placed within a hollow post, or tube and which, when driven therefrom, after the post has been set in the ground, will automatically unfold and extend laterally from 15 the axis of the post, thus presenting resisting surfaces whereby to prevent the possibility of the post being pulled upward, or otherwise forced from its seat in the ground.

Another object of my invention is to 20 provide a lock for the anchor, which automatically becomes effective when the anchor has become fully extended and whereby to prevent it from collapsing and being pulled back into the post by an upward pull on the 25 post, after it has once been driven therefrom.

Other and further objects of my invention will become readily apparent, to persons skilled in the art, from a consideration 30 of the following description when taken in conjunction with the drawings; wherein:—

Figure 1 is a central vertical section of a hollow post, or tube showing the folded or collapsed anchor therein before being driven therefrom. Fig. 2 is a similar view taken in a plane at right angles to Fig. 1. Fig. 3 is a section taken on line 3—3 of Fig. 1. Fig. 4 is a section taken on line 4—4 of Fig. 2. Fig. 5 shows a sectional view of 40 the post with the anchor partly driven therefrom. Fig. 6 shows a slightly modified post with the anchor entirely driven therefrom and automatically locked. Fig. 7 illustrates another form or modification 45 that my invention may take. Fig. 8 shows the anchor partly extended. Fig. 9 is a sectional view on line 9—9 of Fig. 8. Fig. 10 is a transverse section taken on line 10—10 of Fig. 7. Fig. 11 is a section taken on line 50 11—11 of Fig. 7.

In all the views the same reference characters are employed to indicate similar parts.

20 is a hollow post or tube preferably provided with an attachable pointed end 21, telescopically connected in the lower end of

the post, as by rivets 22. While the part or point 21 contributes to easy driving of the post into the ground it is by no means essential to its operation, for in many instances I may entirely do away with and not use the point. When the point 21 is used I prefer to taper the inner portion 23, as at 24 to provide anchor guides.

The post is preferably provided with oppositely disposed openings 25 and 26, at the bottom of the guides, through which the members of the post anchor will pass as will be more fully hereinafter described.

The anchor consists, preferably, of a head 27 to which are pivotally connected, horns or arms 28 and 29, each of which is preferably outwardly curved, as at 30, the lower points of which substantially touch the inner edge of the tube or post. It is now evident that if the head 27, and the attached horns 28 and 29, be driven down into the post, as by means of a rod or hammer 32, that the curved ends 30—30, of the members 28 and 29, will enter the perforations 25 and 26, made through the walls of the post, and being curved they will be projected outwardly, as they progress downwardly into the earth, into positions shown substantially, as in Fig. 5. If the ends 30—30 of the members 28 and 29 are opposite the respective perforations 25 and 26, there will be no difficulty, as a result of the curves, in the ends of the members 25 and 26 entering the said perforations, but if the said ends of the device should be placed at substantial angles, to that shown in Fig. 1, the ends 30—30 will impinge upon the inclined inner, opposite surfaces 24—24, of the point 21, and will thereby be guided or turned into positions so that the points 30—30 will thereby be guided into the perforations, or orifices, 75 80 85 90 95 100 105 110 115 25 and 26, made through the walls of the post, so that in any event the members 28 and 29 will be caused to pass through the perforations 25 and 26. After the members 28 and 29 have been extended, substantially as shown in Fig. 5, if great upward strain were applied to pull the post up it possibly might be pulled from the ground, the members 28 and 29 possibly collapsing and going back into the post, but to prevent this effect I provide an automatic lock for the anchor members, consisting of link members 34 and 35, pivoted together, as at 36, and to each of the members 28 and 29, as at 37 and 38, respectively. The members 28

and 29 are pivoted to the head 27 by a bolt 39 and when they are in the same longitudinal plane they act as toggles to lock the anchor members. Now looking at Fig. 5, when 5 the head 39 is driven down, so that the links 34 and 35 strike the bottom of the perforations 25 and 26, the links 34 and 35 will be straightened out, substantially as shown in Fig. 6, thereby providing a lock which will 10 automatically lock the anchor members 28 and 29 and effectively prevent them from collapsing.

Fig. 6 is substantially the same structure as that shown in Figs. 1 to 5 inclusive, with 15 the exception that instead of using the point 21 I may provide an abutment for the head 27, such as a ring 40, on the inside of the post near the bottom edge, or I may use any other convenient, equivalent means, to prevent 20 the head 27 from passing entirely through the tube or post, and furthermore, I provide a point 41, connected, as at the pivotal point 36, to enter the earth within and under the post and prevent the parts 25 from shifting laterally, or I may adopt the means shown in Figs. 7 to 11 inclusive wherein the post is provided with perforations, substantially the same as perforations 25 and 26, but without a point and in which the 30 members 27 and 28 are not so much curved, as shown in Figs. 1 to 6 inclusive. The point 41, operates upon the link members 34 and 35, and serves to spread the members 27 and 28. In each case the links 34 and 35 35 serve as toggles to lock the members 27 and 28 against possibility of collapsing.

It is manifest, as will appear to one skilled in the art, that my invention is susceptible of many other variations and modifications 40 aside from and in addition to those which I have specifically shown and pointed out, within the scope of the appended claims.

Having described my invention, what I claim is:

45 1. In combination with a hollow post or tube; an anchor, for insertion within the tube and to be driven therefrom after the post has been driven into the ground, com-

prising a head; two arms, or horns, pivoted thereto and two links pivoted together, the 50 free ends whereof are pivoted to the respective horns, to form a toggle lock when the horns are extended.

2. In combination with a hollow post or tube; an anchor, for insertion within the 55 tube and to be driven therefrom, after the post has been driven into the ground, comprising a head; two outwardly curved, pointed arms or horns, pivoted together and two links pivoted together, the free ends whereof 60 are pivoted to the respective horns to lie in the same longitudinal plane, to thus form a toggle lock for the horns when the latter are extended.

3. In combination with a hollow post or 65 tube; an anchor for insertion within the tube and to be driven therefrom, after the post has been driven into the ground, comprising a head; means for preventing the head from being driven from the tube; two outwardly 70 curved, pointed arms, or horns, pivoted to the head and two links pivoted together, the free ends whereof are pivoted to the respective horns, to lie in the same longitudinal plane, to form a toggle lock for the horns 75 after the latter have been driven from the tube.

4. In combination with a hollow open ended post or tube, an anchor, for insertion within the tube and to be driven therefrom 80 after the tube has been placed in the ground, comprising a head, two arms or horns pivoted thereto, two links pivoted together with their free ends pivoted to the respective horns to form a toggle lock when the horns 85 are extended, and a ground engaging member carried by the anchor at the point of pivotal connection between the two links substantially as and for the purpose set forth.

In testimony whereof I hereunto set my 90 hand in the presence of two subscribing witnesses.

ARTHUR W. SPRAGUE.
